DEVICE FOR DEFORMING ONE OF A PLURALITY OF INTERFITTING PARTS TO LOCK SAID PARTS TOGETHER

Fred W. Doering, Cicero, John P. Jones, Chicago, and James C. Morison, La Grange, Ill., assignors to Western Electric Company, Incorporated, New York, N. Y., a corporation of New York

Application December 8, 1953, Serial No. 396,874

5 Claims. (Cl. 78—1)

This invention relates to a device for deforming one of a plurality of interfitting parts to lock said parts together and more particularly to a tool for supporting a pair of apertured plates with a wire threaded through perforated tabs on the plates and for flattening the wire to secure it to said plates.

An object of the invention is to provide a device for supporting a plurality of interfitting parts and deforming one of said parts to secure said parts one to another.

A further object of the invention is to provide a tool for supporting a pair of plates having perforated tabs with a wire passing therethrough and for flattening the wire on opposite sides of the tabs to secure the wire thereto.

Another object of the invention is to provide a device for supporting a pair of plates having perforated tabs with the end of a U-shaped wire passing therethrough and for flattening the wire on opposite sides of the tab to secure the wire thereto and for moving the wire longitudinally relative to the plates to permit the flattening of said wire at different places thereon.

One type of device illustrating certain features of the invention may include a central block or punch holder and a pair of end blocks or punch holders mounted on opposite sides of said central block for movement toward and away therefrom for receiving between the central and end blocks a pair of apertured plates having sets of perforated tabs thereon and the ends of a U-shaped wire threaded through said perforated tabs. The central block has a set of punches on opposite sides thereof adapted to fit through the apertures in the plates and engage one side of the wire, and the end blocks have a set of punches aligned with the punches on the central block for engaging the opposite sides of the wire, whereby the device, with the parts in position between the blocks, may be placed in a press and the press actuated to impart movement to the punches to flatten portions of the wire and form lateral projections thereon engaging one side of some of the tabs. A handle on the main block on which the looped wire is supported has a movable end portion which is cam actuated from a first position to a second position to move the wire longitudinally from a first to a second predetermined position relative to the plates and to cause the projections on the wire to be moved from engagement with one side of some of the tabs into engagement with the other side of other tabs, after which the device may be again applied to the punch press and actuated to cause the formation of a second set of lateral projections on the wire in engagement with said one side of the tabs for securing the wire to the plates.

Other objects and advantages of the invention will become apparent by reference to the following detailed description and the accompanying drawings illustrating a preferred embodiment thereof, in which

Fig. 1 is a plan view of the device with the wedge plate and tail wire parts assembled thereon and showing the device with the wire shifting head in its extended position;

2

Fig. 2 is an end elevational view of the device showing the wedge plates and wire in assembled position thereon and the end punch holders in open position in full lines and in closed position in dotted lines;

5 Fig. 3 is a vertical cross-sectional view through the device taken on the lines 3—3 of Figs. 1 and 6;

Fig. 4 is a plan sectional view taken on the line 4—4 of Figs. 3 and 6, and showing the lower punch holder;

10 Fig. 5 is a plan sectional view taken on the line 5—5 of Figs. 3 and 6;

Fig. 6 is a vertical longitudinal sectional view taken on the line 6—6 of Fig. 5 showing the wedge plates and tail wide parts thereon, and the movable end punch holders in their closed positions before they have deformed the wire;

15 Fig. 7 is a view similar to a portion of Fig. 6 showing parts thereof in a different position and the wire after it has been deformed;

Fig. 8 is a side elevational view of the tail wire and wedge plates in assembled relation;

20 Fig. 9 is a plan view of a portion of the wedge plate and tail wire in one position of the assembly thereof;

Fig. 10 is a view similar to Fig. 9 showing the wire in a different position;

25 Fig. 11 is a vertical longitudinal section through the wedge plate and the tail wire taken on the line 11—11 of Fig. 10; and

Figs. 12 and 13 are detailed cross-sectional views taken on the lines 12—12 and 13—13 of Fig. 11.

30 The present device 15 is designed to secure the end portions of a U-shaped tail wire 18 to a pair of wedge plates 20 to form a component of a cable supporting device or multiple drop wire clamp. Each of the wedge plates 20 has a set of three tabs 22 punch-formed thereon in predetermined uniform spaced relation to each other along the centerline of the plate, each tab 22 being disposed at right angles to the plate and having a perforation 24 punched therein substantially tangent with the face of the plate. A series of apertures 26 are thus formed in the wedge plate 20 by the punching of the tabs 22 therefrom and an additional circular aperture 28 is punched in the plate in alignment with the apertures 26 and spaced from the adjacent aperture 26 a distance equal to the distance between the apertures 26.

35 The ends of the U-shaped tail wire 18 are inserted through the perforations 24 in the tabs 22 of the pair of wedge plates 20 with the ends of the wires extending through and spaced from the endmost tab 22, as indicated in Fig. 9. The ends of the wire 18 are then deformed to form flattened portions 30 having flat surfaces 31 engageable with one face of the wedge plates and having laterally extending shoulders 32 engageable with the end tab 22. The tail wire 18 is also deformed adjacent to two of the tabs 22 on each plate 20 to form flattened portions 33 having lateral projections with shoulders 34 engaging one side of the tabs. The tail wire 18 is then moved longitudinally to cause the flattened portions 33 to move from engagement with said one side of some of the tabs 22 into engagement with the opposite sides of other tabs 22 and to cause the flattened portions 30 to engage the other side of the end tabs 22 (Fig. 10), after which the wire is again deformed to provide flattened portions 35, the shoulders 36 of which engage a pair of the tabs 22 on said one side on each of the plates

40 20. With the flattened portions 30, 32, and 35 engaging the opposite sides of the tabs 22 and with the flat surface 31 of the flattened portion 30 engaging one of the faces of the wedge plates 20, the end portions of the tail wire 18 are securely fastened to the plate against longitudinal and rotary movement relative thereto.

45 The device 15 comprises a central block or a punch

50 20. With the flattened portions 30, 32, and 35 engaging the opposite sides of the tabs 22 and with the flat surface 31 of the flattened portion 30 engaging one of the faces of the wedge plates 20, the end portions of the tail wire 18 are securely fastened to the plate against longitudinal and rotary movement relative thereto.

55 20. With the flattened portions 30, 32, and 35 engaging the opposite sides of the tabs 22 and with the flat surface 31 of the flattened portion 30 engaging one of the faces of the wedge plates 20, the end portions of the tail wire 18 are securely fastened to the plate against longitudinal and rotary movement relative thereto.

60 20. With the flattened portions 30, 32, and 35 engaging the opposite sides of the tabs 22 and with the flat surface 31 of the flattened portion 30 engaging one of the faces of the wedge plates 20, the end portions of the tail wire 18 are securely fastened to the plate against longitudinal and rotary movement relative thereto.

65 20. With the flattened portions 30, 32, and 35 engaging the opposite sides of the tabs 22 and with the flat surface 31 of the flattened portion 30 engaging one of the faces of the wedge plates 20, the end portions of the tail wire 18 are securely fastened to the plate against longitudinal and rotary movement relative thereto.

70 20. With the flattened portions 30, 32, and 35 engaging the opposite sides of the tabs 22 and with the flat surface 31 of the flattened portion 30 engaging one of the faces of the wedge plates 20, the end portions of the tail wire 18 are securely fastened to the plate against longitudinal and rotary movement relative thereto.

holder 40 having a handle 41 extending from one end thereof and having three apertures 42 therein arranged along the centerline thereof and in predetermined uniformly spaced relation to one another, in which are mounted anvil members 44. The anvil members 44 are secured in the block 40 by pins 45 and have pairs of punches 46-46, 47-47, and 48-48 formed on opposite ends thereof and projecting from the opposite faces 49 and 50 of the block 40. The block 40 extends from one face of and is secured to or formed integral with a plate 53 (Figs. 2 and 3), the ends of which extend in opposite directions beyond the block 40 and are recessed to form a pair of hinge lugs 55 for receiving therebetween hinge pins 59 formed on a pair of end blocks or punch holders 57. Hinge pins 59 pass through bores 60 in the lugs 56 and through slots 61 in the lugs 55 for supporting the end blocks 57 for pivotal movement about the pins 59 and for limited rectilinear movement toward and away from the block 40. The blocks 57 may thus be oscillated to and from open and closed positions, shown in full lines and in dotted lines, respectively, in Fig. 2, and when in closed position, the end blocks 57 may be moved toward each other and the central block 40 therebetween. The forward surfaces 63 on the lugs 55 engage flat surfaces or shoulders 64 on the end blocks 57 and serve as guides for guiding the blocks 57 for movement toward the block 40 in parallel relation thereto. Each of the blocks 57 has a plurality of recesses 65 for receiving a set of punches 66, 67 and 68 aligned and cooperable with the pairs of punches 46, 47 and 48 on the central block 40 for forming the flattened portions, 30, 33 and 35 on the tail wire 18. The ends of the punches 66 and 67 and the ends of the punches 46 and 47 are flat and of a predetermined width and are disposed parallel to the faces of the blocks 57 and 40, respectively. The end surfaces of the punches 68 are disposed obliquely and cooperate with the flat ends of the punches 48, which are disposed parallel to the faces 49 and 50 of the block 40. In closed position, the blocks 57 have outwardly directed parallel faces 69-69, which are spaced from the ends of the hinged lugs 55 and are engageable with pressure applying members, such as is found in presses for imparting movement to the blocks 57 toward each other and the central block 40.

The wedge plates 20 are adapted to be positioned on the block 40 in engagement with the opposite faces 49 and 50 thereof and with the punches 46 and 47 extending through a pair of apertures 26 in the plates 20 and the punches 48 extending through the apertures 28, as shown in Figs. 6 and 7. The tail wire 18 fits around and is supported on the handle 41 of the device in a predetermined position longitudinally relative to the wedge plates 20, as shown in Fig. 6. With the wedge plates 20 and the tail wire 18 in assembled relation on the block 40 and the handle 41 of the device 15 as shown in Fig. 6, the end blocks 57 are moved from their open to their closed positions, as shown in Fig. 6 and in dotted lines in Fig. 2, with the punches 66, 67 and 68 thereof in engagement with the end portions of the wire 18. The device 15 with the parts 18 and 20 therein may then be placed in a press 100 and the press actuated to cause the blocks 57 and 40 to move toward one another and compress the end portions of the wire 18 between the pairs of opposing dies 46-66, 47-67, and 48-68 to deform the wire therebetween and form the flattened portions 33-33 and 30. The ends of the punches 66 and 67 engage one side of a pair of the tabs 22 on each plate 20 and the ends of a pair of the tabs 22 on each plate fit into enlarged end portions of the recesses 65 formed in the blocks 57 and hold the plates 20 against movement to the left, as viewed in Fig. 6. Recesses 70 are provided in the blocks 57 for receiving the third tab 22 on the wedge plates 20. The cooperating punches 46, 66 and 47, 67 engage and press opposite sides of the

wire 18 toward the center thereof to form the flat laterally extending portions 33 along the horizontal central portion of the wire. The outer faces of the punches 48 are substantially flush with the face of the wedge plates 20 during the wire-flattening operation, as shown in Fig. 7, and the end of the punches 68 are positioned for cooperation therewith to press the ends of the wire and form the flattened portions 30 with one face thereof in the plane of the face of the plate 20.

On completion of the formation of the flattened portions 30 and 33 in the tail wire 18, the tail wire is moved longitudinally to disengage the flattened portions 33 from one side of a pair of tabs 22 and to move them into engagement with opposite sides of the adjacent tabs 22 prior to the second operation of forming a pair of flattened portions 35 on the tail wire. Means are provided for longitudinally moving the tail wire 18 relative to the plates 20, which includes a head 72 forming a section of the handle 41 and mounted for movement relative to the handle 41 to and from a retracted position shown in Fig. 6 and an extended position shown in Fig. 1. The handle 41 and the head 72 thereof are provided with grooves 73 and 74, respectively, for receiving and supporting the tail wire 18 therein. The head 72 is fixed to one end of a rod 76, which is slidably supported in a longitudinal bore 77 in the handle 41 and has an enlarged intermediate portion 78 slidable in an enlarged portion 79 of the bore 77. A spring 80 interposed between the enlarged portion 78 and an apertured plug 81 threaded in the end of the bore 77 moves the rod 76 and the head 72 to its forward position and yieldably maintains it in said position. A pin 82 disposed transversely of the handle 41 engages a flat surface 83 on the portion 78 of the rod to prevent the rod 76 and the head 72 thereon from turning. The other end of the rod 76 is engageable with a cam surface 83 of a cam member 84 disposed in a slot 85 and oscillatable about a pin 86 in the handle 41. The cam 84 has an arm 87 extending therefrom which forms a lever by means of which the cam 84 may be moved from a first position to a second position to effect the movement of the head 72 to and from its retracted and expanded positions. Thus, in its retracted position, the head 72 serves to position the tail wire 18 with the end portions of the wire in a predetermined position relative to the plates 20, as shown in Fig. 6. After the flattened portions 30 and 33 have been formed in the wire 18, and in response to the turning of the lever 87 from its dotted line position to its full line position, as shown in Fig. 1, the head 72 is moved to its extended position and serves to move the tail wire 18 longitudinally relative to the plates 20 to the position shown in Fig. 1, with the flattened portions 30 and 33 in engagement with the other sides of some of the tabs 22 of the wedge plates. The device 15, with the parts thereof in this position is again placed in a punch press and the punch press actuated to bump the device and cause relative movement of the blocks 40 and 57 and thereby effect the formation of flattened portions 30 with the laterally projecting shoulders thereof in engagement with one side of a pair of tabs 22 on each plate 20. On completion of the second forming operation, the tail wire is securely attached to the plates 20 and the device 15 may be opened and the tail wire and wedge plate assembly removed therefrom.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A device for deforming a U-shaped part of a plurality of interfitting parts to secure said U-shaped part to the other parts thereof comprising a first holder having two sets of punches disposed in opposite directions, a pair

of second holders each having a set of punches cooperable with a set of the punches on said first holder for deforming portions of said U-shaped part, means mounting said second holders on opposite sides of said first holder and for movement of said holders and the sets of punches toward one another and with portions of said second holders engageable with a pair of pressure applying members for moving said second holders toward each other, means on said holders for supporting the interfitting parts therebetween in a first position relative to each other and for holding said other parts against movement in one direction, and means for moving said U-shaped part relative to said other parts to dispose said parts in a second position relative to each other.

2. A device for securing the ends of a U-shaped wire to a pair of wedge plates to form a component of a cable clamp wherein the plates have a plurality of apertures and a plurality of tabs extending substantially perpendicularly therefrom and wherein the end portions of the U-shaped wire are threaded through the perforated tabs, said device comprising a first holder having a pair of opposed parallel faces engageable with said wedge plates and having a set of punches projecting from each of said faces and adapted to extend into the apertures in said plates and into engagement with one side of the end portions of the U-shaped wire, a pair of second holders disposed on opposite sides of said first holder and each having a set of punches engageable with the other side of said wire and aligned with the punches on said first holder for deforming portions of said wire, means for mounting said punch holders for movement toward and away from one another and with portions of the second holders engageable with a pair of relatively movable pressure applying members, whereby said punch holders with the plates and wire disposed therebetween may be placed in a press and actuated to cause the punches to deform the wire.

3. A device for securing the ends of a U-shaped wire to a pair of wedge plates to form a component of a cable clamp wherein the plates have a plurality of apertures and a plurality of tabs extending substantially perpendicularly therefrom and wherein the end portions of the U-shaped wire are threaded through the perforated tabs, said device comprising a first holder having a pair of opposed parallel faces engageable with said wedge plates and having a set of punches projecting from each of said faces and adapted to extend into the apertures in said plates and into engagement with one side of the end portions of the U-shaped wire, a pair of second holders disposed on opposite sides of said first holder and each having a set of punches engageable with the other side of said wire and aligned with the punches on said first holder for deforming portions of said wire, means for mounting said punch holders for movement toward and away from one another and with portions of the second holders engageable with a pair of relatively movable pressure applying members, whereby said punch holders with the plates and wire disposed therebetween may be placed in a press and actuated to cause the deformation of the wire, a handle extending from said first holder for supporting the U-shaped wire and positioning the end portions thereof in a predetermined first position relative to said plates, and means on said handle for moving said wire to a second position with the end portions thereof in a second predetermined position relative to the plates.

4. A device for securing the ends of a U-shaped wire to a pair of wedge plates to form a component of a cable clamp wherein the plates have a plurality of apertures and a plurality of tabs extending substantially perpendicularly therefrom and wherein the end portions of

the U-shaped wire are threaded through the perforated tabs, said device comprising a first holder having a pair of opposed parallel faces engageable with said wedge plates and having a set of punches with ends thereof projecting from said faces and adapted to extend through the apertures in said plates and into engagement with one side of the end portions of the wire, a pair of second holders disposed on opposite sides of said first holder and having opposed outwardly directed faces against which pressure may be applied to effect movement of the holders towards each other, each of said second holders having a set of punches engageable with the other side of the wire and cooperable with the punches on said first holder for flattening portions of said wire, means on said first holder for mounting said second holders for movement toward and away from one another whereby said device with the plates and U-shaped wire disposed between said first and said second holders may be placed in a press and the press actuated to move said holders toward each other to cause the flattening of portions of said wire, a handle extending from said first holder and having an end section mounted for movement to and from a retracted and an extended position and engageable with a portion of said U-shaped wire for moving it longitudinally from a first position to a second position relative to the plates, and means on said handle for actuating said end section from said retracted position to said extended position.

5. A device for securing the ends of a U-shaped wire to a pair of wedge plates to form a component of a cable clamp, wherein the plates have a plurality of apertures and plurality of tabs extending substantially perpendicularly therefrom and wherein the end portions of the U-shaped wire are threaded through the perforated tabs, said device comprising a first holder having a pair of opposed parallel faces engageable with said wedge plates and having a set of punches with ends thereof projecting from said faces and adapted to extend through the apertures in said plates and into engagement with one side of the end portions of the wire, a pair of second holders disposed on opposite sides of said first holder and having opposed outwardly directed faces against which pressure may be applied to effect movement of the holders towards each other, each of said second holders having a set of punches engageable with the other side of the wire and cooperable with the punches on said first holder for flattening portions of said wire, means on said first holder for mounting said second holders for movement toward and away from one another whereby said device with the plates and U-shaped wire disposed between said first and said second holders may be placed in a press and the press actuated to move said holders toward each other to cause the flattening of portions of said wire, a handle extending from said first holder and having a movable end section engageable with a portion of said U-shaped wire for moving it longitudinally from a first position to a second position relative to the plates, a plunger slidably mounted in said handle for supporting said end section for movement to and from retracted and extended positions, resilient means for moving said end section to and yieldably maintaining it in said retracted position, and cam means mounted on said handle for moving said plunger and said end section from said retracted position to said extended position.
